CLAIM

The ornamental design for a lighting fixture, as shown and described.

DESCRIPTION

FIG. 1 is a perspective view of a lighting fixture showing the new design;

FIG. 2 is an enlarged fragmentary view of the leftmost lamp of the lighting fixture of FIG. 1;

FIG. 3 is a front elevation view of the lighting fixture of FIG. 1, the rear elevation view being a mirror image thereof;

FIG. 4 is a top plan view of the lighting fixture of FIG. 1; FIG. 5 is a bottom plan view of the lighting fixture of FIG. 1;

FIG. 6 is a left side elevation view of the lighting fixture of FIG. 1; and,

FIG. 7 is a right side elevation view of the lighting fixture of FIG. 1.

The broken lines shown on the drawings depict portions of the lighting fixture that form no part of the claimed design.
